DRAG BUCKET

Jesse F. Yaun, Baton Rouge, La.

Application March 12, 1945, Serial No. 582,308

1 Claim. (Cl. 37—135)

1

This invention relates to drag buckets and it is primarily an object of the invention to provide a bucket of this kind constructed in a manner whereby the same is relatively light in weight but assembled and reinforced in a manner to give the same requisite strength.

It is also an object of the invention to provide a bucket of this kind constructed in a manner whereby the drag line may be effectively hitched to the bucket as well as the dump line.

A still further object of the invention is to provide a bucket of this kind provided with tooth elements including points which can be readily applied or removed.

The invention consists in the details of construction and in the combination and arrangement of the several parts of my improved drag bucket whereby certain important advantages are attained, as will be hereinafter more fully set forth.

In order that my invention may be the better understood, I will now proceed to describe the same with reference to the accompanying drawings, wherein:

Figure 1 is a view in side elevation of a drag bucket constructed in accordance with the present invention.

Figure 2 is a view in front elevation of the same.

Figure 3 is a view in top plan of the bucket.

Figure 4 is a vertical longitudinal section taken on the line 4—4 of Figure 3.

Figure 5 is a central longitudinal section on a vertical plane through a tooth and adjacent portions of the bucket bottom and hood.

Figure 6 is a view in top plan of a complete tooth removed from the bucket.

Figure 7 is a sectional view taken substantially on the line 7—7 of Figure 4.

Figure 8 is a view in side elevation of a modified form of the bucket construction.

Figure 9 is a horizontal sectional view taken substantially on the line 9—9 of Figure 8.

In the embodiment of the invention as illustrated in Figures 1 to 4, the body B of the bucket comprises a bottom wall 1, side walls 2 and a rear wall 3 preferably formed of relatively light sheet metal and with the rear wall 3 disposed on a predetermined curvature from its lower part to its top and with the lower marginal portions of the side walls 2 inwardly curved or rounded, as at 4.

The butting edges of the side walls 2 and bottom wall 1 and the butting margins of the rear wall 3 and side walls 2 are rigidly secured together by welding. The forward end portion of

2

the bottom wall 1 is bent downwardly whereby said forward end portion transversely is disposed on an arc with the outbow downwardly directed.

5 The bottom wall 1 terminates a distance inwardly of the forward extremities of the side walls 2 and the lower portions of the side walls 2 forwardly of the bottom wall 1 are cut away, as at 5, to facilitate the digging action of the bucket.

Surrounding the forward end portion of the body B is a reinforcing hood H in close contact at substantially all points with the bottom wall 1 and side walls 2 of the body B and with the upper edges of the side members 6 of the hood H substantially flush with the upper edges of the side walls 2.

The hood H has its forward edges substantially flush with the forward edges of the side walls 2 and said side members 6 extend a material distance inwardly of the bucket B with the inner or rear edges of said side members 6 extending downwardly and outwardly on a predetermined curvature. This hood H is welded to the body B.

20 The lower forward portions of the side members 6 of the hood H are cut away, as at 7, in a manner substantially conforming to the cut-away portions of the side wall 2 and the forward edge of the bottom part 8 of the hood H is formed with a downward and forward bevel 9, with said beveled portion 9 extending beyond the bottom wall 1 of the body B, whereby said beveled portion 9 provides a digging blade, the efficiency of which is facilitated by the cut-away portions 5 and 7.

35 Bridging the forward end of the body B and disposed thereabove is a curved plate 10 of desired radius and which has its end edges resting upon the forward portions of the upper edges of the side members 6 of the head H and welded thereto. The forward edge of the plate 10 is flush with the forward edges of the side member 6 of the hood H.

40 Resting upon the top of the plate 10 is a reinforcing member 11 of channel form and which member is of such size as to have its extremities overlie the upper portions of the hood H. The side flanges a of this reinforcing member 11 have direct contact with the plate 10 and are secured thereto by welding. The lower portions of these flanges a are also in direct contact with the side member 6 of the hood H and secured thereto by welding; and the lower or free ends of the part of the channel member 11 lying between the flanges a are curved inwardly, as at 12, to close

said end portions of the member 11. This member 11 is also of a width closely approximating the width of the curved plate 10.

At the central or high portion thereof the member 11 has disposed transversely thereacross a hood socket connection S. As herein embodied, this connection S comprises a pair of spaced but closely adjacent upstanding lugs 14 having their upper margins inclined downwardly and forwardly, as at b, with the rear high portions of the lugs 14 provided with the openings 15 and 16 through which is directed the holding pin 17 for the dump rope socket P, herein illustrated as a single eye type, and with which is operatively engaged an end portion of the dump rope 18. The opening 15 has its outer portion angular in contour to receive the head 19 of the pin 17 to prevent turning of the pin.

Secured to each side wall 2 and the adjacent side member 6 of the hood above but immediately adjacent to the cut-away portions 5 and 7 is a hitch plate 20 with a portion thereof extending beyond the adjacent edges of the hook H and body B. The plate 20 is rigidly held in place by the rivets 21 or otherwise as may be preferred.

The forwardly extending portion of each of the plates 20 is provided with transverse slots 22 to receive a load shackle, not shown.

The portions between the slots are apertured to form vertically spaced aligned eyes 22' to receive a suitable lock pin, not shown, by which the shackle is retained in working position.

Upon the top of the plate 20 are formed the upstanding perforated ears 29 to receive a holding pin, not shown, which, when applied, is disposed across the aligned eyes 22' to hold against upward displacement a lock pin inserted through the eyes.

Carried by the side walls 2 of the body B exteriorly thereof are the trunnion units T. Each of these units comprises a plate 31, herein disclosed as substantially rectangular, and which is riveted, as at 32, or otherwise rigidly secured to a side wall 2 of the body B at a point rearwardly of the longitudinal center of the body B. The plate 31 at a desired point between its top and bottom margins is provided with an outstanding flange 33, the outer margin of which is continued by an upstanding relatively large wing 34.

The upper portion of this wing 34 is provided with an opening 35 which is in alignment with an opening, not shown, in the plate 31, and the opening 35 and the opening of the plate 31 receive a pin 37 which bridges the space between the wing 34 and plate 31 to engage through a rigid trunnion link such as is shown at 39, in Figure 8.

The outer extremity of each of the trunnion links 39 is adapted to have coupled thereto, as by the pin 45, in Figure 8, an end portion of a hoist chain 46 which is operatively engaged, as at 47, in a conventional manner with a suitably operated block-and-tackle or other element whereby the bucket may be raised or lowered. As diagrammatically illustrated in the accompanying drawings, this block-and-tackle or kindred element includes a sheave 48 for the dump rope 18.

Associated with the entering or digging edge of the bottom of the body B are the digging teeth A of desired number and spaced apart transversely of the body B. Each of these digging teeth comprises two sections 49 and 50, the section 49 constituting a base member and the section 50 a removable point member.

The base member or section 49 comprises an

elongated arm 51 which underlies the forward portion of the bottom member 8 of the hood H and is welded or otherwise securely attached thereto. The forward portion of the arm 51 is provided with an upwardly and rearwardly disposed lug 52 which extends across in close contact with the beveled digging edge 9 and extends inwardly thereof in close contact with the upper face of the forward portion of the bottom 1 of the body B and is welded or otherwise rigidly secured thereto.

The front portion of the lug 52 and the adjacent end portion of the arm 51 constitute a head 53, the outer face c of which is disposed on a predetermined downward and rearward incline. This face c is provided centrally with an elongated wedge-like arm 54 with the smaller end portion outwardly disposed. The rear portion of this arm 54 has disposed transversely therethrough a slot-like opening 55 which is adapted to register with the slot-like openings 56 in the side walls 57 of the tapered socket 58 in the rear end portion of the point 59.

A tapered key 60 is insertible through the registering openings 55 and 56 whereby the point 59 is effectively yet removably held in applied position. The smaller end portion of the key 60 is bifurcated, as at 61, to allow said smaller end portion to be spread, after the key 60 has been applied, to hold the key against accidental displacement.

It is to be noted that each of the arms 54 is disposed on a forward and downward incline and is of such length that when a point 59 is secured thereon the outer or digging end of said point will be below the bottom member 8 of the hood H.

The upper marginal portions of the side walls 2 and the rear wall 3 are provided therealong with the reinforcing strips 62 to prevent buckling or bending of such walls.

Underlying the bottom wall 1 of the body B and rigidly secured thereto, as by welding, are the runners 63 which are continued upwardly over the back or rear wall 3. These runners 63 also serve to materially strengthen or reinforce the bottom wall 1 and the rear wall 3. The reinforcing strips 62 extending along the upper margins of the side walls 2 are welded to the rear edge of the hood H.

In the embodiment of the invention as illustrated in Figures 8 and 9, the general construction and assembly are substantially the same as hereinbefore disclosed with respect to the first embodiment of the invention except that the hood 55 Y in itself comprises the front portion of the bucket body and the rear portion is of a skeleton structure to permit the draining off of liquid or fine materials as determined by the size of the openings in the walls of said rear portion.

The rear portion X comprises longitudinally disposed parallel strips 64 suitably coupled together. The forward end edges of the strips 64 butt the rear edge of the bottom 66 of the yoke Y and are welded thereto. The rear portions 65 of the strips 64 are continued upwardly, as at 67, to provide the back or rear wall of the body.

Each of the side walls of the rear portion X of the bucket body comprises the longitudinally or horizontally disposed spaced parallel strips 70 between which are interposed suitably spaced vertical or cross members 71 having their end edges butting longitudinal edges of the strips 70 and welded thereto, with the lower members 71 having their bottom ends butting and welded to the outer side strips 64 of the bottom wall.

The hoods H and Y can also be called lip plates and by adding one or more hoods or lip plates Z, as illustrated in Figure 8 of the drawings, a standard weight bucket X may be increased to a weight of an extra heavy type depending, of course, on the number of hoods or lip plates added.

From the foregoing description it is thought to be obvious that a drag bucket constructed in accordance with my invention is particularly well adapted for use by reason of the convenience and facility with which it may be assembled and operated.

I claim:

A drag bucket comprising a relatively long body open at the top and at the front end, the body having a bottom portion which is transversely arcuate at the forward edge and which curves downwardly through a portion of its length at said forward edge, a reinforcing hood enclosing the bottom and sides of the forward end of the body and having a forwardly and downwardly curving bottom portion which extends beyond the forward edge of the bottom portion of the body, a plurality of tooth members each having a relatively long bottom arm and a relatively thick rounded lug of materially less length than and overlying and spaced from the arm, the space between the arm and the lug forming a slot for the reception of the forward edge portion of the bottom portion of the hood, the distance between

the rear end of the lug and forward end of the slot substantially equaling the longitudinal extent of the forward portion of the hood beyond the bottom of the body whereby the rear end of said lug butts against the forward edge of the bottom portion of the body when the tooth is secured to the bottom portion of the hood, the top of the lug curving downwardly and rearwardly with respect to the top surface of the bottom portion of the body, and means for attaching drag and hoist lines to the bucket, the said forward edge of the bottom portion of the body being under-cut and the curved top of the lug extending downwardly and rearwardly beneath and butting against the under-cut surface of the forward edge of the bottom portion of the body.

JESSE F. YAUN.
